J. J. BABKA

OIL ATOMIZER

Filed Oct. 13, 1923

— Inventor —
Joseph J. Babka

Richardson Atty.

UNITED STATES PATENT OFFICE.

JOSEPH J. BABKA, OF BERWYN, ILLINOIS.

OIL ATOMIZER.

Application filed October 13, 1923. Serial No. 668,268.

My invention relates in general to oil atomizers, and the principal object is to provide a new and improved centrifugal atomizer for oil burners of the well known rotary type, such as is shown and described in the U. S. patent to Ray, No. 1,385,376, granted Nov. 19, 1918. By an improved construction, I am able to obtain a much more perfect atomization of the ordinary grade of fuel oil, which materially assists in securing the essential intimate mixture of the oil atoms with the air which is required for perfect combustion.

While as stated my improved atomizer is designed especially for rotary oil burners, its use is not necessarily so limited, but it may be used to atomize oil for delivery to an oil engine, or for other purposes; and a further object, therefore, is to provide a centrifugal atomizer for use with internal combustion engines, making it possible to operate such engines on much lower grades of oil than have heretofore been considered practicable.

The foregoing and other objects and the means by which the same are accomplished will be described fully hereinafter, reference being had to the accompanying drawing, which shows a cross section through the nozzle of a rotary oil burner equipped with my improved atomizer.

Referring to the drawing, the reference character 1 indicates the nozzle of the burner, which it will be understood is adapted to enter a suitable opening in the front of the furnace, while the reference character 2 is a motor driven shaft which rotates the atomizer and fan (not shown). The usual vanes for directing the air current are indicated at 3 and 4. These parts are all of well known construction.

The atomizer is attached to the end of shaft 2 and comprises two cup shaped members 5 and 6, preferably of bronze, and having a peculiar configuration which is shown clearly in the drawing. The rear cup 5 is provided with a hub 20, which is attached to the end of shaft 2 by means of internal screw threads as shown. In addition, the rear cup 5 has a forwardly extending inner ring 7, which is threaded externally on the end to receive the threaded portion of the front cup 6. Thus both cups are firmly secured together and to the shaft, while at the same

time they are readily detachable for inspection, cleaning, or repairs.

Outside the inner ring 7, the rear cup 5 has a series of projecting rings or concentric annular flanges 8, 9, and 10, which interlock, so to speak, with a corresponding series 11, 12, 13, and 14 on the front cup. That is, the several flanges are arranged alternately on the inside and outside of cups 5 and 6, respectively, and form a series of connected annular spaces between the two cups. Each flange preferably has a curved inner surface, on the order of a parabola, the curvature being greatest where the flange joins the cup and gradually decreasing in both directions. The edge of each flange is sharp and clean cut, and lies in close juxtaposition to the curved surface of the opposite flange.

Oil is fed to the atomizer through the pipe 15, which is carried inside the hollow shaft 2, and is discharged through a goose neck extension 16 into the central chamber formed by ring 7. A series of slots such as 17 permit the passage of oil through the walls of the chamber. A metal disc 21, with up turned edge, is held in place by friction, and closes the inner chamber just in front of the slots 17.

The shaft 2 is preferably sealed against the entrance of air at the end opposite the atomizer, but is provided with a port 22 which may be entirely or partially closed by a tight fitting rotatable sleeve 23.

The operation is as follows: When the motor is started shaft 2 is rotated at high speed, rotating the atomizer with it, while at the same time the fan causes a strong current of air to flow through the annular air discharge passage between the atomizer and the inner surface of the nozzle. As oil is delivered through pipe 15 it is discharged onto the inner surface of ring 7, where it has imparted to it a rotational velocity which causes it to spread in a film (due to centrifugal force), and whence it eventually escapes through the slots 17 and strikes the flange 11. Upon reaching flange 11 the oil again spreads in a film and flows toward the rear over the curved surface of the flange until it is discharged off the edge onto flange 8. The direction of flow is then reversed, and the oil flows over the surface of flange 8 toward the front until it is discharged onto the next flange 12. Continuing in this

manner the oil flows over and is discharged from the remaining flanges in succession, and finally, after being atomized, reaches the annular discharge orifice at the edges of the 5 two cups, whence it is discharged into the path of the air current, is mixed with the air, and is consumed.

Since the annular air current completely surrounds the annular oil discharge orifice 10 an injector action is set up which assists in the discharge of the atomized oil. The air port 22 may be entirely closed, in which case the atomizing chamber is sealed against the entrance of air, or it can be opened to any 15 desired extent to provide a regulated current of air through the atomizing chamber which mixes with the oil as it is atomized and to some extent modifies the process.

The exact process by which the oil is 20 atomized is more or less obscure, since it cannot be observed, but in general the operation is thought to be about as follows: As the oil flows over the first flange it of course attains substantially the same rotational 25 velocity as the flange itself and is discharged over the edge in a film each component particle of which takes a direction tangent to the circular edge of the flange. This film then strikes the next flange, where some 30 atomization may take place due to impact, but at any rate, the film formed on the next flange is thinner because of the increased rotational velocity imparted to the oil and because of the increased area of the flange. 35 Thus the film formed on each succeeding flange is thinner than the film formed on the preceding one and eventually the film becomes so thin that the surface tension is overcome and the molecules are released. 40 A considerable variation in oil supply is possible in accordance with the amount of heat required. In order to enable a very small quantity of oil to be handled with uniformity the end of the goose neck 16 45 is preferably adjusted quite close to the inner ring 7 so that the rotating surface will pull the oil evenly out of the opening and prevent the formation of drops.

As mentioned before my improved atomizer is not limited to the particular use above 50 described but has utility for other purposes. For instance, by the provision of a suitable housing over the air discharge cone, the mixture of oil and air can be carried a reasonable distance through pipe to a remote 55 furnace, or if desired, the mixture of oil and air can be utilized as an explosive compound for an oil engine.

While I have shown and described a certain specific embodiment of my invention, I 60 am aware that changes and modifications may be made, as will no doubt occur to persons skilled in the art, and I do not therefore wish to be held to the precise form and construction shown, but desire to include and

have protected by Letters Patent all forms of my invention which come fairly within the scope of the appended claims.

What I claim is:

1. In an oil atomizer, a cup shaped member having a series of annular flanges on the inside thereof, and a second cup shaped member positioned inside said first member and having a series of annular flanges on the outside thereof. 70

2. In an oil atomizer, an atomizing chamber, two alternate series of annular flanges projecting within said chamber from opposite ends thereof, and two concentric flanges extending forward from the opposite 80 ends of said chamber, respectively, said last mentioned flanges being spaced apart to form an annular passage for conducting atomized oil from said chamber.

3. In an oil atomizer, two members forming a short cylindrical chamber, a series of concentric annular flanges projecting into said chamber from one end thereof, a second overlapping series of similar flanges projecting into said chamber from the other end, 90 and means for discharging atomized oil from said chamber in a direction substantially parallel to said flanges.

4. In a rotary oil atomizer, a short cylindrical atomizing chamber, an annular discharge opening at one end of said chamber, means for introducing oil at the center of 95 said chamber, and a series of concentric annular baffles between the point at which the oil is introduced and said discharge opening. 100

5. In an oil atomizer, a plurality of concentric annular flanges, means for introducing oil within the inner flange, a shaft for rotating the atomizer to cause the oil to flow over said flanges successively, and a cylindrical member outside said flanges for directing the atomized oil in a direction substantially parallel to said shaft. 105

6. In an oil atomizer having an atomizing chamber and an elongated annular discharge 110 passage, means for introducing oil in said chamber, means for rotating the atomizer to cause the oil to flow through said chamber toward said opening, and a series of baffles extending parallel to said discharge passage 115 for changing the direction of the oil a plurality of times.

7. In an oil atomizer, a hollow shaft, a member secured to the end of said shaft, a ring and a series of flanges projecting from the face of said member, a second member secured to said ring and positioned adjacent the ends of said flanges, a second series of flanges projecting from said second member and alternating with the flanges of said first series, an opening in said first member opposite the end of said shaft for introducing oil within said ring, and an opening in said ring for allowing the oil to escape onto the first of said flanges. 120 125 130

8. In an oil atomizer, a cup shaped member having a series of flanges on the inside projecting forward from the bottom thereof, a projecting ring inside the inner flange, a 5 second member secured to the end of said ring and enclosed within the walls of the said first member, and a second series of flanges projecting backward from said second member and arranged alternately with 10 the flanges of said first series.
9. In a fuel oil burner, the combination, with a tubular nozzle, of an oil atomizer positioned inside said nozzle and spaced apart therefrom to form an annular air passage, 15 means for introducing oil inside said atomizer, a series of baffles for conducting the oil over a devious path through said atomizer in a general direction perpendicular to said air passage, and means for discharging the atomized oil in a direction substantially parallel to said air passage. 20
10. In a fuel oil burner, the combination, with a tubular nozzle, of an oil atomizer posi- tioned inside said nozzle and spaced apart therefrom to form an annular air passage, 25 means for introducing oil inside said atomizer, a series of baffles for conducting the oil over a devious path through said atomizer and means for discharging the atomized oil in an annular stream having the same general direction as the direction of the air stream through said air passage. 30
11. In an oil atomizer, a plurality of concentric annular flanges, means for introducing oil within the inner flange, means for 35 rotating the atomizer to cause the oil to flow over said flanges successively, means for discharging the atomized oil in an annular stream, and means for preventing the flow of air through the atomizer to the inside of 40 the stream of atomized oil.

Signed at Chicago, county of Cook and State of Illinois, this ninth day of October, 1923.

JOSEPH J. BABKA.
